CLAIM

The ornamental design for a softstarter, as shown and described.

DESCRIPTION

FIG. 1 is a front right side isometric view of a softstarter in accordance with the new design;

FIG. 2 is a front side elevational view thereof;

FIG. 3 is a rear side elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line portion of the figure drawings is included to show portions of the article that form no part of the claimed design.
